APPARATUS FOR APPLYING PIGMENT COATINGS

Application filed November 19, 1928. Serial No. 149,435.

This invention is concerned with apparatus for the application of liquid coatings and pigments to articles to be coated and has for its general object the provision of an apparatus adaptable to the coating of bulky and heavy articles of irregular shape.

Other objects of my invention include the provision of an apparatus of the character referred to which will operate with a minimum degree of attention and operate either continuously or if desired, intermittently when the objects to be coated are placed therein. A further object is the provision of a coating machine which will apply a liquid coating to objects having irregularly shaped surfaces, depressed surfaces and overhanging portions. Other objects include economy in labor and preservation of the pigment solvent while maintaining a uniform consistency of the material being applied to the objects being coated.

Other objects of my invention will hereinafter become apparent from the following description which refers to the accompanying drawings illustrating a preferred embodiment thereof. The essential characteristics are summarized in the claims.

In Fig. 1, I show a vertical cross-section of a coating machine embodying the principles of my invention; Fig. 2 is a partial cross-sectional plan view of the machine; Fig. 3 is an enlarged cross-sectional detail of the receiving end of the machine; Figs. 4 and 5 are enlarged cross-sectional details taken along the lines 4-4 and 5-5 of Fig. 3 and showing means for controlling an intermittent flow of pigment; Fig. 6 is a fragmentary detail of the control shown in Figs. 4 and 5; Fig. 7 is an enlarged cross-sectional detail of an automatically operated valve disposed in a piping circuit comprising a circulating system for the pigments; Fig. 8 is a fragmentary view of the valve shown in Fig. 7; Fig. 9 is an enlarged view of a pigment nozzle comprising part of the pigment circulating system; Fig. 10 is a cross-sectional detail taken along the line 10-10 of Fig. 9.

My invention contemplates the provision of a machine which is particularly adaptable to the application of coatings of pigments to

heavy bulky objects which cannot be coated by the use of ordinary industrial spreading apparatus now in use. I provide a conveyor system in association with a housing or canopy wherein a series of pigment nozzles are arranged to project sheets or filaments of liquid coating at desired angles relative to the object to be coated whereby corners, crevices and the end surfaces of overhanging portions of the object may be completely and thoroughly coated without the entrapping of air bubbles. Nozzles are a part of a pigment circulating system which includes a pigment gathering or splash tray disposed beneath the housing and a dripping tray and piping connected to the gathering tray. The nozzles and piping are connected with a pump whereby a constant circulation of the pigments may be maintained. The nozzles are mounted within the housing in such manner that thin sheets or pigment may be projected toward the object at an angle to both the vertical and horizontal to insure the complete and entire coating of the exposed surface of the object to be coated.

In the drawings and particularly in Fig. 1, I show an enclosure comprising a housing wherein are disposed nozzles 17 having slots 17a formed therein (see also Figs. 9 and 10) through which slots the sheets of liquid coating may be projected toward the object from opposite sides of the housing. At 18, I show a transversely extending nozzle for coating the end surface of the object as will be hereinafter described. At the bottom of the housing is disposed a conveyor 20 and beneath the conveyor, the pigment gathering or splash tray 21 of a hopper shape at the bottom of which are screens 22 and 23 through which the pigment may pass through a reservoir 24. The bottom of the reservoir is connected to a pipe 25 leading to a pump 26, preferably driven by a motor 27. Leading from the pump 26 is an upwardly extending pipe 30 which branches adjacent the top of the housing and extends thereinto along the sides thereof to afford a connection for the nozzles 17 and 18. The housing is provided with an entrance door 32 and an exit door 33. Leading to the entrance door 32 is a con-

veyor 34 for bringing objects to the housing. The conveyor 34 is aligned with the conveyor 20 disposed within the housing whereby an object may be automatically transferred 5 to the interiorly disposed conveyor 20. The door 32 is automatically opened and closed, if desired, in a manner to be hereinafter described. The exit door 33 may also be automatically opened and closed consequent to a 10 movement of the object by the conveyor 20 whereby the coated object may be transferred to the drip conveyor 35 beneath which is placed a drip tray 36. The respective conveyors may be driven through suitable power 15 transmission by a motor 37 (see Fig. 2). The power transmission is such that the drip conveyor 35 will move at considerably less speed than the interiorly disposed conveyor 20 to afford sufficient time for the surplus 20 coating to drain from the coated object. The door at 33 may also be automatically operated as will be hereinafter described.

As shown in Fig. 2, the conveyor 34 may be driven directly by the motor through a 25 belt 40 extending over a pulley 41 mounted on an outer end of a conveyor shaft 42. The shaft 42 is suitably supported in brackets 43 attached to the housing structure 15 of the machine. The shaft 42 carries a sprocket 46 30 which drives a chain 47 which extends longitudinally of the housing but on the outside thereof to drive the sprocket 48 mounted on the conveyor shaft 49. The shaft 49 carries a second sprocket 50 which drives the sprocket 35 chain 51. The sprocket chain 51 extends over a sprocket 52 which is carried by conveyor shaft 53 of the drip conveyor 35.

The machine may be operated continuously insofar as the pump and pigment circulating system are concerned, but if it be desired to operate the machine intermittently or at least effect an intermittent action of the nozzles, a valve such as is shown in Fig. 7 40 may be placed in the pigment circulating pipe 30 near the entrance door 32. This valve may comprise an apertured slide member 60 exposed within the valve casing 61 to interrupt passage of pigment to the upper 45 member of the pipe 30. A spring 63 tends to maintain the valve in closed position. A projection 64 is placed on a door 32 whereby when the door has been permitted to swing to a closing position after the work has passed 50 through the door opening, the door will maintain the valve in the open position shown in Fig. 7. When the valve is in closed position, the pump continues to work and an excess pressure valve 66 is provided in a by- 55 pass line 69 (see Fig. 1) to permit the pigment to circulate only through the reservoir and pump when the valve is closed. If desired, this valve may also be controlled by 60 swinging movement of the exit door 33 whereby the pigment circulation may be arrested 65

in the housing until the new piece of work makes entrance thereto through the door 32.

In Fig. 3, I show a door actuating and latching mechanism operated by movement of the conveyor 34 for controlling the operation of the entrance door 32. This mechanism may comprise a slotted bracket member 74 in the slot of which rides a pivot pin 75 connecting a link 76 with a slide block 77. The link 76 is attached to a lug 32a on the door 32. The bracket 74 is suitably secured to the housing 15. Lugs 34a are provided on the conveyor which may be adjusted to any desired spaced relation on the conveyor depending upon the number of pieces of work being carried thereby. These lugs 34a are adapted to engage the slide block 77 whereby the door 33 will be swung to the dot and dash position shown in Fig. 3 being forced by movement of the conveyor 34. The lug 34a escapes from its engagement with the slide block 77 in passing over conveyor sprockets 34b. During the engagement of the lug 34a with the slide block 77, the pivot pin 75 is brought into engagement with the latching member 80 pivotally mounted on the inner end of the bracket 74 near the door 32 whereby the door is retained in open position shown in dotted lines until the second lug 34c (see Fig. 4) engages the lower end 80a of the latch 80 thus freeing the pin 75 and link 76 to permit the door 32 to drop to closed position. The lugs 34a and 34c are adjustably attached to the conveyor 34 in predetermined spaced relation whereby the object will have sufficient time to be moved on the conveyor 20 into the housing to clear the door 32 when the latter drops to closed position. When the door 32 drops to closed position the valve 60 is opened so that pigment flows in the pipe 30 from the pump and through the nozzles 17 and 18. As the object is moved by the conveyor past the nozzles and toward the exit end of the housing 15, the door 33 is swung upwardly to an open position by a link and slide mechanism (see Fig. 1) similar to the mechanism shown in Fig. 3 for the inlet door 32. The lugs 20a are attached to the conveyor 20 in predetermined positions so that the door 33 will be opened only as the work approaches the exit of the housing. If desired a connecting mechanism such as a bar 85 may be provided to connect the doors 32 and 33 whereby upon the first movements of the opening of the door 33, the valve 60 will again be closed by the spring 63 to arrest the passage of the pigment to the nozzles.

One of the novel features of my invention is to be found in the manner in which I support the nozzles 17 and 18 in the housing. As shown in Figs. 1 and 9, the nozzles 17 are suspended from a bracket 90 to which is attached an adjustable link 91 having perforated ends disposed at right angles to each

other and carrying connecting members 92 and 93 adjustably secured together by any suitable means such as screw members 94. The end of the nozzle is provided with a large cylindrical portion 97 which is engaged by an annular clamping member 95 which is secured to the member 93 and clamping bolt 96. As will be apparent from Fig. 9, this arrangement will permit the positioning of the longitudinal nozzle member 17 to extend into any angle oblique to both the horizontal and vertical within the confines of the housing and the nozzle slot 17a may be turned to any degree by adjustment of the clamp 95 so that the sheets of pigment being projected by the nozzles toward the object may be projected in any desired plane depending upon the particular shape of the object to be coated. Flexible conduits 98 serve to connect the nozzles with the circulating pipe 30 to permit the adjustment of the nozzles. Similar mounting is provided for transversely extending nozzle 18.

From the foregoing description of my invention, it will be understood that I provide a coating machine for applying pigment to bulky and heavy objects, the objects being moved into the housing by a conveyor whereupon they are transferred to a second conveyor entirely disposed within the housing so that a minimum of pigment is carried out of the housing. Thereafter the object is transferred to a third conveyor moving at a considerably slower speed which permits the surplus pigment carried by the object to drain therefrom and drop to a collecting tray, which returns the collected pigment to the reservoir of the circulating system. It is to be further understood that the doors of the housing may be omitted. Also the intermittent pigment control is simply supported by the housing to provide for the splash incident to the operation of the nozzles. This machine is operable with practically no manual effort on the part of the operator and serves to provide against evaporation of the solvent carrying the pigment to a considerable extent. It maintains the pigment solution at that consistency which is best adapted to the obtaining of a maximum pigment spray and by maintaining the pigment in constant circulation, all foreign matter coagulations and the like may be collected by the screen and thereby prevented from clogging the nozzles.

I claim:

1. A pigment applying machine having in combination oppositely disposed pigment nozzles having elongated apertures adapted to discharge films of pigment, a pigment circulating system including a pump and a drip tray disposed beneath the nozzles, said nozzles being connected in the pigment circulating system by a universal connection to permit the adjustment of the nozzles where-

by the nozzles may project opposed films of pigment toward the object being coated at angles obliquely to a vertical and a horizontal plane, a housing enclosing the nozzles and the drip tray, and a conveyor disposed within the housing.

2. In an apparatus of the character described, the combination of an elongated housing, a conveyor therein, a pigment dripping tray disposed beneath the conveyor, an adjustable elongated pigment projecting nozzle disposed within the housing, a pigment circulating system including a pump connected to the nozzle and to the lower region of the drip tray, a second conveyor leading from the housing and means adapted to drive the two conveyors at different speeds.

3. In an apparatus of the character described, the combination of an elongated housing, a conveyer therein, a pigment dripping tray disposed beneath the conveyer, an adjustable elongated pigment projecting nozzle disposed within the housing, a pigment circulating system including a pump connected to the nozzle and to the lower region of the drip tray, and by-pass valve means for controlling the passage of pigment through the nozzle and which is responsive to the movement of an object to be coated when moved by the conveyer.

4. In an apparatus of the character described, the combination of an elongated housing, a pigment dripping tray disposed at the bottom of the housing, an elongated pigment projecting nozzle disposed within the housing at an angle oblique to the vertical and horizontal, a pigment circulating system including a pump connected to the nozzle and to the lower region of the drip tray, means for moving an object through the plane of projection of the projected pigment and by-pass valve means responsive to the movement of the object for controlling an intermittent operation of the nozzle.

5. In a pigment applying machine the combination of an elongated housing, a conveyer disposed therein, a pigment collecting tray disposed beneath the conveyer, oppositely disposed pigment projecting nozzles having elongated apertures or slots arranged within the housing, to extend at an oblique angle relative to the vertical and horizontal and a pigment circulating system connecting the nozzles and the pigment collecting tray including a pump, and also including a transversely disposed nozzle, the respective nozzles being adjustable to any angle within the limitations of the housing.

In testimony whereof, I hereunto affix my signature.

EDWARD P. LANG.
